Attorney,

UNITED STATES PATENT OFFICE.

BONAVVENTURE ZERENGA, OF BROOKLYN, NEW YORK.

TOY VEHICLE.

1,324,096.

Specification of Letters Patent.

Patented Dec. 9, 1919.

Application filed February 17, 1919. Serial No. 277,619.

To all whom it may concern:

Be it known that I, BONAVVENTURE ZERENGA, a citizen of the United States, residing at Brooklyn, in the county of Kings and State of New York, have invented certain new and useful Improvements in Toy Vehicles, of which the following is a specification.

This invention has relation to toy vehicles 10 of the tricycle type, and has for its primary object to provide an article of this character in which the body is formed in the shape of a horse or other animal.

Another object of the invention is to provide a toy vehicle of the character above set forth embodying a pair of wheels located rearwardly, and a forward single steering wheel mounted for steering motion around a vertical axis, the wheel being steered by 20 means of a post which extends through the body of the horse or other animal forming the seat.

A still further object of the invention is to provide a toy vehicle and having the 25 characteristics above set forth in which the two fore-legs of the animal are mounted for rotation about a vertical axis in order to secure steering, the steering wheel being located between said forelegs, said steering 30 wheel also having pedals whereby the vehicle may be propelled.

A still further object of the invention is to provide a novel means for connecting together and bracing the forelegs so that they 35 may be rotated during steering of the device and whereby all possibility of weakening of the structure as a result of such connection is eliminated.

A still further object of the invention is to 40 provide a toy vehicle as stated above in which the details of construction have been carefully worked out with a view to insuring great durability for the toy and to minimize the cost of construction thereof to 45 the greatest extent possible.

In addition to the foregoing, this invention comprehends improvements in the details of construction and arrangement of parts, to be hereinafter described and particularly set forth in the appended claims.

In the accompanying drawings in which similar and corresponding parts are designated by the same characters of reference throughout the several views in which they 50 appear—

Figure 1 is a view in perspective of a toy

vehicle constructed in accordance with my invention.

Fig. 2 is a view of the forward portion thereof in side elevation, with parts broken away.

Fig. 3 is a detail view in front elevation, with parts broken away of the upper end of the forelegs.

Fig. 4 is a top plan view of the upper ends of the forelegs.

Fig. 5 is a detail view in section of the upper portion of the rear legs showing the manner in which they are connected to the body.

Fig. 6 is a detail section taken on the line 6—6 of Fig. 2.

Fig. 7 is a bottom plan view of one of the rear legs illustrating the manner in which the same is connected to the axle and

Fig. 8 is a view of the part shown in Fig. 7 in side elevation.

With reference to the drawings, 10 indicates the body of the toy which may be formed in the shape of a horse or other animal having the neck and head 11 formed integrally therewith or separately as desired. The forelegs indicated at 12 are made separately from the body and mounted between the forelegs is the front steering wheel 13 mounted upon an axle 14 which is offset at opposite ends as at 15 and said ends are supplied with pedals 16, thereby permitting the user to propel the device after the manner of a tricycle. The rear legs indicated 90 at 17 are mounted at their lower end upon an axle 18 rigidly secured thereto, and mounted upon the ends of the axle are rear supporting wheels 19. With reference to Fig. 2 it will be noted that the forelegs are supplied with metallic horse shoes 20, and secured to the underside thereof are semi-circular flange bearings 21 through which the axle 14 extends. With reference to Figs. 7 and 8 it will be noted that the rear legs are 100 likewise provided with horse shoes of a slightly different type illustrated at 22, and the axle 18 extended through a pair of semi-circular clips 23, each clip having a lateral extension 24 which is apertured to receive a lag screw 25 which enters the material of which the hind legs 17 are constructed to secure the clips in place and to rigidly secure the axle 18 against movement.

Referring again to the forelegs 12 it will 110 be noted that they are connected together rigidly at their upper end by means of a

cross cleat shown at 26 in Figs. 3 and 4. One of the essential features of my invention is the manner in which the legs are secured together since it will be noted that 5 the ends of the cross cleat 26 are split or formed with a series of spaced reeds 27 having their upper edges coinciding with the upper surface of the cleat and having their lower edges curved as at 28 in Fig. 3. 10 These reeds enter correspondingly formed recesses 29 in the inner surface of the forelegs 12, and before assembling the parts glue is applied to the meeting surfaces of the several parts in order that a firm joint 15 may be secured which is readily obtained by this means. A recess 30 is formed in the upper surface of the cleat 26 to receive a steering post 31 which extends through a vertical opening formed in the forward portion 20 and neck of the body 10, a lag screw 32 being subsequently entered into the cleat 26 and into the steering post 31 as shown in Fig. 2. A circular recess 33 is formed in the underside of the forward portion of 25 the body 10, and a second recess 34 is formed concentrically relative to the recess 33. A metallic washer 35 is seated in the recess 33 and the steering post is entered therethrough, a metallic pin 36 being subsequently inserted through an opening in 30 the steering post and permitted to play within the recess 34. The metallic washer 35 is held in place through the medium of lag screws 37 which penetrate the body 10, and it will thus be noted that the steering post 31 is held in place against the displacement while at the same time it is permitted to 35 rotate. Careful reference to Fig. 2 will disclose the fact that the steering rod 31 is inclined upwardly at a slight angle with a view to facilitating steering of the toy. A cross piece 38 is secured to the upper end 40 of the steering post as shown.

Toys of this character heretofore constructed of wood have been prone to become 45 easily broken by a slight jar due to the fact that the equivalents of the cross cleat 26 were formed with dovetails to seat in corresponding recesses in the legs of the animal. 50 The entire structure was thus weakened and the legs were frequently split longitudinally at their point of connection with the cross cleat. In Fig. 5 I have illustrated the manner in which the rear legs 17 are connected 55 to the body 10. In this case a cleat 40 is

provided having the reeds 41 which enter recesses 42 formed in the adjacent faces of the legs similar to the manner set forth in Figs. 3 and 4. However, the cleat 40 is secured to the underside of the body 10 by 60 means of lag screws 43. If glue is applied to the surfaces first a firm and solid connection will be effected. It will be seen from the foregoing that I have devised a means shown clearly in Figs. 3 and 4 where- 65 by the legs may be securely held together without weakening the part, and it has been found in practice that this method is very effective and eliminates all trouble previously caused by breakage. Other points 70 of novelties and advantages in my invention will be readily apparent to those skilled in the art to which this invention appertains.

While I have illustrated and described my 75 invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what 85 I claim as new and desire to secure by United States Letters Patent is:

1. A toy horse including a body, a pair of legs said legs having their upper ends and inner faces recessed at several places, 90 a cross bar to connect the upper ends of said legs, a plurality of reeds on each end of said cross bar to enter said recesses, and screws entering said cross bar on the underside of the body to secure said legs in place. 95

2. A toy horse including a body, a pair of forelegs having their upper surfaces and sides recessed or formed with semi-circular recesses at various places, a cross bar, a plurality of semicircular reeds on the ends of 100 said cross bar to enter the recesses, said cross bar having a recess in its upper surface, a post extending through the body and entering said recess and the brace, and means securing said post to the bar. 105

In testimony whereof I affix my signature in presence of a witness.

BONAVVENTURE ZERENGA. [L.S.]
